UNITED STATES PATENT OFFICE

2,180,889

ACOUSTIC ASSEMBLY FOR THE HARD OF HEARING

Christian A. Volf, New York, N. Y., assignor to
Clarence W. Sinn, New York, N. Y.

Application July 1, 1936, Serial No. 88,434

2 Claims. (Cl. 179—1)

This invention is an acoustic assembly, primarily for use by the hard of hearing.

One of the important objects of the invention is to provide an assembly which carries its own electrical supply, so that it does not need to be plugged into any commercial circuit. The independence of this invention of any commercial circuit makes it useable at any point, regardless of different voltages, etc., met with in various parts of the country. Many hearing aids using commercial lighting circuits also are subject to objectionable overheating, which is entirely avoided by this invention.

Due to the fact that the assembly is entirely self-contained, with its own electrical supply, the invention is very readily portable, and can be placed in any desired position on a desk, table, conference table, dining table, bedroom, and may be used in an automobile, in the woods, at the beaches, and in theaters, churches and lecture halls, etc.

Another important advantage of the invention is that it is highly sensitive so that it will pick up relatively weak or faint sounds. But it is sensitive only in a definite or fixed direction, so that it can be placed to pick up the desired sounds, such as the conversation of an individual, or the words of a minister or lecturer, but at the same time it will exclude other extraneous and undesirable sounds coming from other directions.

The transmitter assembly of this invention is conveniently placed in a suitable carrying case and put into use simply by opening a portion or front slide, for example, of the case, without the necessity of removing the entire instrument.

The main advantages of the invention having thus been outlined, the present preferred structural embodiments of the invention will now be briefly described.

The invention comprises a concave sound concentrator, mounted in a suitable housing, and in front of this sound concentrator and spaced from it, there is mounted a transmitter of more or less standard design, in such a position that sound waves picked up by the concentrator will be directed onto the receiving face of the transmitter. Mounted on the outer face of the transmitter there is a substantially hemispherical cup, which serves the purpose of deflecting sound waves into the concentrator, and also of providing a resonant chamber or air cushion on the inside thereof, back of the transmitter. The back of the transmitter may be provided with suitable apertures, opening into this resonant chamber, thus

putting this resonant chamber in communication with the resonant chamber in the transmitter.

The transmitter assembly also carries its own battery, which may be a dry cell or cells of known design, which is also mounted in its own housing. 5

A magnetic amplifier is mounted for electrical connection both with the battery and the transmitter, and is preferably arranged to plug directly into the battery or dry cell.

There is also preferably provided, in the assembly, a voltmeter, which may be connected by a push button switch to the battery as desired for reading the condition of the battery at any time. A suitable housing is also provided for the voltmeter. 10

However, in place of the voltmeter, there could be mounted a clock, a barometer, a thermometer, a crystal radio set, or other desired type of apparatus. The use of such other instruments such as barometers, clocks, etc., would tend to camouflage the instrument as an instrument for use by the hard of hearing. 15

The desired housings for the sound concentrator, for the battery, and for the instrument, such as a voltmeter, clock, barometer, etc., may 25 be made in several ways, such for example, as a single casting having three compartments. The housing may be made of metal, aluminum, Bakelite or other synthetic resin, etc. This casting might be integral with a base or detachably 30 secured to a base, the wires being concealed in the base.

The several housings are preferably separated by partition walls and where such partition walls are metallic, they would serve to prevent inductive effect from one instrument to the other. 35

Where the several housings are made of wood, they could be cut from a single block of wood, or could be made in three separate units, which could be glued, dove-tailed, or otherwise fastened 40 together.

The several component parts of the invention, as will appear from the drawings, are assembled into an attractive and well proportioned instrument which would ordinarily not be recognized 45 as an aid for the hard of hearing, and at the same time is distinctly ornamental, attractive, and modernistic in appearance, all of which features are important in an article of this sort.

Reference will now be made to the accompanying drawings, illustrating in more detail the preferred embodiments of the invention. 50

In these drawings:

Fig. 1 is a perspective view of the acoustic assembly;

- Fig. 2 is a plan view;
 Fig. 3 is a side elevation of the control side;
 Fig. 4 is a wiring diagram;
 Fig. 5 is a side view of a modification; and
 Fig. 6 is a side elevation of the receiving side of Fig. 5.

Referring now to these drawings, in which similar reference characters indicate similar parts, the assembly comprises a suitably recessed base 2, on which is mounted a housing 4, for a concave sound concentrator 6, the sound concentrator being conveniently in the shape of a segment of a sphere, although it could have other curvatures, parabolic, for example, if desired. The concentrator is preferably made of spun pewter, which has been found particularly efficient for this purpose. The housing 4 is preferably of the simple rectangular form shown. Mounted directly in front of the sound concentrator 6 and spaced therefrom is a transmitter 8, which may be of usual design, but is preferably of the type shown in my Patent No. 2,118,993, dated May 31, 1938, having a concave receiving face 10, facing toward the concave surface 25 of the concentrator 6. The transmitter 8 is mounted in place by means of a small tube or pipe 12 secured by means of a bushing 14 to the concave face 10 of the transmitter, this pipe 12 passing through the housing 4 and being rigidly held in place by means of a lock nut 16 and washer 17, the latter being secured to pipe 12 and to concentrator 6. The usual wires 41, 42 from the transmitter 8 pass into the tube 12 through a suitable slot, thence through the tube 12, for connection to a rheostat and amplifier, as will be described.

The tubular supporting member 12 engages with the transmitter 10 and with the sound concentrator 6 substantially at their centers, leaving the peripheral portions of the transmitter and sound concentrator unobstructed for picking up sound waves. The tube 12 is quite small and for this reason also presents a minimum of interference. Furthermore, this tube 12 seems 45 to act as a resonance member in transmitting sound vibrations from the sound concentrator 6 to the transmitter 10. As is evident from Fig. 2 the tubular support 12 is substantially coincident with the central transverse axis 18 of the concentrator 6 and the transmitter 10.

Mounted on the back of the transmitter 8 is a substantially hemispherical cup or cap 22. Sound waves coming toward the device flow around the cup and thence onto the concentrator 55 6. The interior of the cup also provides a resonance chamber or air cushion which is in communication by means of apertures 24 with the resonance chamber provided by the inside of the transmitter, back of the diaphragm. The 60 interaction of those two resonance chambers lowers the pitch and improves the tone quality of the instrument.

The electrical supply for the apparatus is a dry cell or cells 26 mounted in a housing 28, also rectangular like the housing 4, but somewhat narrower and lower than the housing 4.

Mounted on top of the housing 28, in a suitable recess, is a magnetic amplifier 30, of a standard or usual design, which is adapted to 70 plug directly into the battery 26 by means of plugs 32, the battery 26 being provided with suitable terminal-forming apertures for receiving these plugs.

A third housing member 34 is provided, preferably of rectangular shape, but smaller and nar-

rower than the housing 28, this housing being for a voltmeter 36 or for a clock, thermometer, barometer, or any other suitable apparatus, which instrument would tend to camouflage the apparatus as a hearing aid.

The three housing members 4, 28 and 34 form a graceful, well-proportioned assembly of simple yet harmonious lines, which is of considerable importance in an article of this type, one of the important uses of which is on an office desk. The several housings 4, 28 and 34 may conveniently be made of a single casting of metal or synthetic resin, such as Bakelite, for example, with partitions between the several housings to provide separate compartments, which are open 15 at the bottom. Where the housings are of metal, the partitions serve to prevent local inductive effects from one compartment to the other.

The several housings 4, 28 and 34 could also be made of wood, either by cutting them out 20 from a single block of wood or by making them separately from smaller blocks of wood and gluing or otherwise securing them together so as to form substantially one unit, having compartments opening downwardly.

The several housings are mounted in the recessed base 2, the housings being positioned in the recess so that most of the wiring will be in the recess directly below the several housing elements.

Referring to the wiring diagram of Fig. 4, the transmitter 8 is connected by wires 41, 42 to the combined switch rheostat 40 which, in turn, is connected by three wires 41', 42' and 43 to the amplifier 30 and battery 26.

Leading from the other side of the amplifier 30 are wires 44 leading to a bone or air induction receiver 45, of usual design.

Wires 41', 42' and 43 are plugged into one end 40 of the amplifier 30 with a three-way plug, while wires 44 are plugged into the other end of the amplifier with a two-way plug.

The voltmeter 36 is connected to the battery 26 by means of wires 46 leading through a push button switch 47 mounted in the base 2.

The several wires, for convenience of inspection and repair, may be connected to terminal elements 48 in the terminal block 50, which is mounted in a concealed position in the recess of the base member 2, underneath the several 50 housings.

Referring now to the modifications shown in Figs. 5 and 6, the concave sound concentrator 6, made of pewter, is mounted in a housing 52 having an ornamental top 54.

Mounted in front of the concentrator 6 is a substantially hemispherical cup 22', secured in position by a plurality of arms 56, secured by bolts or screws 58 to the housing 52. The arms 56 are substantially U-shaped in cross section, to provide a channel 60 therein facing toward the concentrator 6.

Mounted in the open end of the hemispherical member 22' is a transmitter 8' of the same general structure as the transmitter 8. The back of the transmitter is provided with apertures 24' so that the resonance chamber inside the transmitter is in communication with the resonance chamber or air cushion inside the hemispherical cup, an arrangement which improves the reception and clarity of the instrument, and lowers the pitch.

The wires 20 from the transmitter are concealed in the recess 60 in one of the arms 56 75

and thence lead into the magnetic amplifier 30', similar in all respects to the amplifier 30 of Fig. 3.

The battery 26 in Fig. 5 is mounted in a housing 62, similar in shape to housing 52, but narrower and shorter than housing 52 and provided with an ornamental top 62' like top 54 of housing 52. On the inside of the ornamental top 62' is mounted the amplifier 30' in a concealed position. The amplifier 30' plugs into the battery 26 as before.

A third housing 64 is provided, which has an ornamental top like 54 in Fig. 6, this housing, however, being narrower and lower than the housing 62. In this housing is mounted a voltmeter 36 or other device such as a clock, thermometer, barometer, etc.

The several housings 52, 62 and 64 may be made in a one-piece casting of metal or synthetic resin, or may be made of wood, as has been described, the compartments of the several housings opening downwardly and in communication with a relatively large recess 66 in the base 68. Inside the base 68 is mounted a plate 70 for supporting the wiring, the wiring block 50, etc.

The several parts in Figs. 5 and 6 are wired as shown in Fig. 4, the base member 68 being provided at any suitable point with a switch 47.

for the voltmeter and with a combined rheostat and switch 40 for the transmitter.

While the preferred embodiments of the invention have been illustrated in some detail, it should be understood that the invention is not limited to such details, but may be carried out in other ways.

I claim as my invention:

1. A sound-pick-up device for use on a table or desk, comprising in combination, a concave sound concentrator, a housing therefor, a transmitter positioned in front of and spaced from the concentrator and facing it, and having a resonance chamber therein, and a substantially hemispherical cup mounted on the back of the transmitter, for directing sound waves into the concentrator and for providing a second resonance chamber back of the transmitter, the back of the transmitter being provided with apertures for putting said resonance chambers into communication with each other, said second resonance chamber serving to lower the pitch and improve the quality of the sound waves that are directed to the transmitter by said concentrator.

2. The combination as claimed in claim 1, wherein the transmitter and the said hemispherical cup are both supported by a support substantially coincident with the central transverse axis of the sound concentrator.

CHRISTIAN A. VOLF. 30
